Primary Examiner — Darlington Ly(57) **CLAIM**

The ornamental design for a public lighting fixture, as shown and described.

DESCRIPTION

1. Public lighting fixture

1.1 is a top, front, and right side perspective view of a public lighting fixture showing our new design;

1.2 is a front elevational view thereof;

1.3 is a rear elevational view thereof;

1.4 is a right side elevational view thereof;

1.5 is a left side elevational view thereof;

1.6 is a top plan view thereof; and

1.7 is a bottom plan view thereof.

The broken lines in the reproductions illustrate portions of the public lighting fixture that form no part of the claimed design.

1 Claim, 7 Drawing Sheets(56)
